WINDING AND TIGHTENING MECHANISM

Application filed October 8, 1930. Serial No. 487,225.

The present invention relates to winding and tightening mechanism.

The present invention has been illustrated and will be described in connection with winding and tightening mechanism applicable to hectograph machines. It will be understood, however, as the description proceeds, that the invention is not limited to hectograph machines, but has a much wider field of application.

Referring particularly to hectograph machines, it may be explained that in the operation of such machines a sheet of gelatin is laid upon a smooth surface, usually flat, and a master copy is impressed upon said surface so that the ink from said master copy is taken off onto the surface of the gelatin sheet. The sheets of paper are then laid upon the gelatin sheet under a slight pressure, so that the ink from the gelatin sheet is taken up. According to the hectograph principle, it is a practical matter to make as many as a hundred copies from a single impression upon a gelatin sheet.

In practice it is common to provide the gelatin sheets in the form of bands which take the form of rolls, the gelatin portion being secured to a fabric or other backing. The roll is mounted upon a spindle which is carried at one end of the bed. The other end of the gelatin sheet or band is secured to a spindle at the other end of said bed. It will be readily appreciated that in order to perform proper duty the gelatin band should be held taut, and, further, that means should be provided for moving the gelatin band along the bed to provide fresh surfaces for the hectograph or copying operation. It is also useful to be able to rewind the gelatin band under certain circumstances. The varying relative speeds of rotation of the copying band spindles due to increase or decrease in diameter as the copying band is wound from one spindle to the other has al-

ways been the subject of considerable attention in the design of duplicating or hectograph machines.

An object of the present invention is to provide a novel winding, stretching and rewinding mechanism by means of which the posi-

tion of any part of the copying band may be simply and quickly adjusted.

A further object is to provide a winding and stretching mechanism in which the necessary movements for accomplishing winding and stretching may be accomplished by a simple movement of a unitary mechanism.

A further object is to provide a winding, stretching and rewinding mechanism in which the winding, stretching and rewinding operations may be performed by simple operation.

A further object is to provide a novel, winding, tightening and rewinding mechanism having readily operable means for winding the band in either direction and tightening said band.

A further object is to provide a winding and rewinding mechanism in which it is necessary in winding or rewinding to operate only the mechanism involved in that operation, thereby obviating the complications due to variable speeds of the copying band spindles as the diameter of the roll upon each spindle varies.

A further object is to provide a winding and rewinding mechanism which will drive one spindle positively and will automatically disengage from the other or following spindle in such a manner that the following spindle will be free to rotate without the necessity of dragging any part of the mechanism with it.

A further object is to provide a winding and rewinding mechanism which through simple mechanism elements will effect the positive engagement with either spindle at will and the simultaneous disengagement of the other spindle.

A further object is to provide brake or clutch mechanism in connection with each spindle, said brake or clutch mechanism being so related to the remainder of the mechanism that adjustment of the copying band can be made in an infinite number of positions.

A further object is to provide a novel winding, tightening and rewinding mechanism in which the operating parts may be located in a position convenient to the operator.

A further object is to provide a winding,

tightening and rewinding mechanism in which the liability that an operator may carry out the wrong sequence of operations is reduced to a minimum.

5 A further object is to provide a mechanism for winding and tightening which mechanism is also provided with means for rewinding, but which rewinding mechanism will interfere in no way with the regular winding
10 and tightening operation of said mechanism.

A further object is to provide a winding and tightening mechanism which may be operated with a minimum of effort and in a minimum of time.

15 A further object is to provide a novel winding and tightening mechanism in which the speed ratios between the operating means and the spindles may be readily changed.

20 A further object is to provide a simple construction in which wear will be reduced to a minimum.

A further object is to provide a mechanism which will lend itself readily to extension to any desired length by simple expedients.

25 A further object is to provide a construction of the character above referred to in which the necessity for accurate machining and locating of the parts is avoided.

30 A further object is to provide a positive and simple means for shifting from a winding to a tightening operation or from a tightening to a winding operation.

35 A further object is to provide a winding and tightening mechanism, the parts of which may be shipped as units and which may be readily put together in the field by inexperienced operators in case replacement should be necessary.

40 A further object is to provide a construction which adapts itself readily to standardization of parts, so that the number of different parts which must be manufactured and stored will be reduced to a minimum.

45 A further object is to provide a winding and tightening mechanism which responds immediately to the action of the operating handle or other means.

50 A further object is to provide a winding and rewinding mechanism for a copying band which will accomplish the winding and rewinding operations with a high degree of mechanical efficiency.

55 A further object is to provide a mechanism of the kind referred to which can be housed entirely in a single frame located at the adjacent ends of the copying band spindles.

A further object is to provide a winding mechanism so constructed that the operator may accomplish the tightening operation with a minimum of effort.

A further object is to provide a simple mechanism of the kind referred to which may be manufactured at low cost and in which the necessity for highly skilled artisans in the

manufacture of said mechanism may be reduced.

Further objects will appear as the description proceeds.

Referring to the drawings—

Figure 1 is a sectional view of a portion of a hectograph machine embodying the present invention, the parts being located in position for a tightening operation, this figure being taken along the plane indicated by the arrows 1—1 of Figure 2;

Figure 2 is a sectional view taken along the planes indicated by the arrows 2-2 of Figure 1;

Figure 3 is a sectional view taken along the planes indicated by the arrows 3-3 in Figures 1 and 4;

Figure 4 is a sectional view taken along the plane indicated by the arrows 4-4 of Figure 3;

Figure 5 is a sectional view taken along the plane indicated by the arrows 5-5 of Figure 2;

Figure 6 is a sectional view taken along the planes indicated by the arrows 6-6 in Figure 2;

Figure 7 is a sectional view indicating a detail of construction, and

Figure 8 is a view of a handle which cooperates with the remainder of the mechanism.

Referring first to Figures 1 and 2 it will be noted that a pair of side frames 10 and 11 are provided. The said side frames are secured together by means of a plurality of cross braces, one of which is shown in Figure 2 and is indicated by the numeral 12. Securely fixed to the side frame 11 is the bracket 13. The frame 11 houses certain winding and tightening mechanism to be described in detail hereafter. Attached to the inner side of the frame 11 at the rear and forward ends thereof are brackets 13, 13, which may be identical with one another. Said brackets provide supports for the spindle operating mechanism at the two ends of the machine at the right side thereof as the parts are viewed in Figure 2. The side frames 10 and 11 provide supporting means for a bed plate 14 which provides a smooth surface for a gelatin band indicated by the numeral 15. As indicated above, the gelatin band is in the form of a roll. In the operation of hectograph machines a roll (mounted upon a spool or spindle) is located at one extremity of the machine, preferably the rear extremity. The free end of the gelatin band 15 is secured to a spindle or other rotatable means located at the opposite end of the machine. The spindle at the rear of the machine in the embodiment of the present invention is illustrated in Figure 2 and is indicated by the numeral 16. Said spindle is shown as having a roll of the gelatin band disposed thereon. The spindle 16 is journaled for rotation.

tion within the side frames 10 and bracket 13 and ordinarily one extremity of the spindle 16 will be formed with a round bearing whereby to be freely rotatable in a journal. The 5 left hand extremity of the spindle 16, as the parts are viewed in Figure 2, may be provided with a smooth journal. The right hand extremity of said spindle 16 will be formed with a non-round contour whereby it may be 10 readily engaged by a rotatable member for the purpose of communicating a positive movement of rotation to said spindle 16. The structure of the spindle and the mountings therefor for communicating rotary movement 15 to said spindle form no part of the present invention and need not be described in detail. Spindles and mountings therefor suitable for the purpose are well known commercially. It will be sufficient to state that the spindle 16 20 may be positively rotated in either direction of rotation by means of the stub shaft 18, which stub shaft is coaxially disposed relative to the spindle 16 and is rotatably supported by an arm 19 fast with the bracket 13. 25 The spindle at the forward end of the machine is indicated by the numeral 20 (Figure 3). It may be stated briefly that one extremity of said spindle 20 has a non-round contour at one extremity thereof whereby it 30 may be positively driven by the stub shaft 21 disposed coaxially with the spindle 20. Said stub shaft 21 is rotatably supported by means of the arm 19 fast with the bracket 13 near the forward extremity of said side frame 11. 35 The stub shaft 18 connected with the rear spindle 16 and the stub shaft 21 connected with the forward spindle 20 are provided with spiral gears 23 and 24, respectively. Said spiral gears 23 and 24 are adapted to co- 40 operate with matching spiral gears 25 and 26, respectively, which spiral gears 25 and 26 are disposed upon the shaft indicated as a whole by the numeral 27. The said shaft 27 will be described more in detail presently, but for 45 the present it may be stated that said shaft is mounted in a manner to have axial movement, which axial movement is very important in the operation of the illustrated embodiment of the present invention. Said 50 shaft 27 comprises the tubular member 28 which houses at its rear extremity the shaft 29 and at its forward extremity the shaft 30. The shaft 29, at the rear extremity of the machine, may be secured to the tubular member 55 28 by means of the pin 31. Near its forward extremity the tubular member 28 is provided with an abutment 32 extending across said tubular member which abuts one extremity of a coil spring 33 housed within said tubular 60 member 28. The other extremity of said spring 33 abuts the shaft 30. The shaft 30 is provided with a cross pin 34 adapted to ride within the slot 35 in the tubular member 28. The shaft 30 is therefore nonrotatably 65 but extensibly secured to the tubular member

28. The shaft 29 at the rear of the machine has fixed thereto the spiral gear 25 and the shaft 30 at the forward extremity of the machine has fixed thereto the spiral gear 26. Inasmuch as the shafts 29 and 30 form part of the drive shaft 27, it will be clear that said spiral gears 25 and 26 will operate in unison. The shaft 29 at the rear of the machine is provided with an enlarged portion 36 which forms a shoulder 36a. Disposed within the 70 enlarged portion 36 is the annular groove 36b. The spiral gear 25 abuts against the shoulder 36a. A sleeve 36c, pinned to the shaft 29 abuts the other side of said spiral gear 25. The sleeve 36c and enlarged portion 36 of shaft 29 are supported within bifurcations 37 and 38 of the arm 19. The shaft 30 at the forward extremity of the machine is provided with a sleeve 39 adapted to slide within the bifurcation 38 forming part of the arm 19 (Figure 3). The bushing 39 is disposed against one side of the spiral gear 26. Disposed upon the other side of the spiral gear 26 is an enlarged portion 41 of the shaft 30 which provides a shoulder 41a disposed on the other side of the spiral gear 26. Said enlarged portion 41 is slidably supported by the bifurcation 37 of the arm 19. The crank 43 is provided for communicating turning movement in either direction to the drive shaft 27. The crank 43 will be described more in detail presently. 80

As noted above, the stub shafts 18 and 21 are coaxial with the spindles 16 and 20, respectively. 85

By referring to Figure 1 it will be noted that the spiral gears 25 and 26 carried by the shaft 27 are spaced apart a distance less than the spacing of the axes of stub shafts 18 and 21. Inasmuch as the shaft 27 is axially movable, this spacing results in the advantage that the spiral gear 25 may be engaged with its mating gear 23 to the exclusion of engagement between the spiral gear 26 and its mating gear 24. Conversely, engagement between the spiral gear 26 and its mating gear 24 may be had to the exclusion of engagement between the spiral gear 25 and its mating gear 23. The spacing between the spiral gears 25 and 26 will be so chosen that as the shaft 27 moves axially one of said gears 25 or 26 will engage with its corresponding mating gear before disengagement of the other of said gears 25 and 26 from its corresponding mating gear. More specifically, if the shaft 27 is moved to the right from the position shown in Figure 1, engagement between the spiral gear 26 and its mating gear 24 will occur before disengagement has occurred between spiral gear 25 and its mating gear 23. 90

The pitch angles of the spiral gears referred to will be chosen of the same value so that the meshing and demeshing referred to may be readily accomplished. 95

It will be understood without detailed explanation that as the shaft 27 is turned if the particular stub shaft 18 or 21 should be non-rotatably held, as for example, by means 5 which will be described presently, a reaction will be set up to move the shaft 27 with its gears 25 and 26 axially. This action will be referred to with more particularity in the description of the mode of operation, which 10 description will follow presently.

The stub shaft 18 at the rear of the machine is provided with an overrunning clutch or brake, which, for the purpose of this description will be indicated as a whole by the numeral 44. The stub shaft 21 at the forward end of the machine is provided with the overrunning clutch or brake which will be indicated as a whole by the reference numeral 45. The clutches 44 and 45 may be similar in 20 construction and a description of the clutch 44 at the rear of the machine will suffice for a description of both of said clutches. Referring particularly to Figures 2, 5 and 7, the stub shaft 18 has fixed thereto the housing 46. Said housing 46 has the smooth circumferential inner wall 47. Disposed coaxially with the stub shaft 18 is the wedging member 48 which is provided with a plurality of tapering recesses 49. In the illustrated 25 embodiment of the present invention three of such tapering recesses are shown symmetrically disposed relative to the axis of the stub shaft 18. The wedging member 48 is fast relative to the side frame member 11. Said recesses 49-49 are defined by the walls 50-50. Each of said recesses houses a roller 51 adapted to roll freely within the large portion of its corresponding recess. Each roller 51 is pressed by a spring 52 toward the small 30 extremity of the corresponding recess. Also disposed within each recess 49 is a pin 53 located within the small portion of its corresponding recess. The three pins illustrated are carried by the rotary plate 54, which 35 plate is rotatably carried by the stub shaft 18. Said rotary plate is provided with an extension pin 55 adapted to be engaged by certain mechanism to be described presently. At this time it may be stated that if the plate 40 54 be rotated in a counter-clockwise direction, as the parts are viewed in Figure 5, the pins 53 will engage the rollers 51, holding them out of the smaller portions of the recesses 49-49, whereby said rollers 51 will be ineffective to control the connection between 45 the wedging member 48 and the housing 46.

By reference to Figure 2, it will be noted that the wedging member 48 is secured to the bracket by means of the pin 56. The rotary 50 plate 54 is provided with a notch indicated by the numeral 57 whereby to provide clearance relative to the pin 56, permitting the necessary rocking movement of said plate 54.

As stated above, the overrunning clutch or 55 brake 45 at the forward end of the machine

is similar in construction to the overrunning clutch 44 just described at the rear of the machine. The mechanisms for controlling said overrunning clutches 44 and 45 will now be described.

Referring to Figure 5, it will be noted that the bracket 13 is provided with a pair of bosses 58-58 which are provided with axial bores for slidably receiving the short shaft 59. Disposed upon said short shaft 59 is the abutment member 60, said abutment member 60 being secured to shaft 59 by means of the machine screw 61 (Figure 2). Said abutment member 60 is provided with a relatively narrow outer edge 62 having an arcuate outer face 63. Said narrow edge rides within the groove 36b (Figure 1) and the arcuate face 63 contacts with the bottom of said groove. By reason of the arcuate engagement between the outer face of the abutment member 60 and the bottom of said groove 36b, the abutment member 60 is properly positioned relative to the portion 30 of the shaft 27. It will be clear that as the shaft 27 is moved axially, the sides of the groove 36b will co-operate with the abutment member 60 in causing a like movement in the short shaft 59. The abutment member 60 is adapted to engage the extension pin 55 as the short shaft 59 is moved toward the right in Figure 5, thereby moving the pins 53 into engagement with the rollers 51 and urging them toward the large portions of the recesses 49 against the tension of the springs 52. When the short shaft 59 is in such a position that the abutment member 60 does not engage the extension pin 55, the springs 52 will be operative to urge the rollers 51 toward the small portions of the recesses 49 whereby to effectually lock the member 46 against rotation relative to the wedging member 48 in a clockwise direction as the parts are indicated in Figure 5.

The control means for the overrunning clutch or brake 45 at the forward end of the machine will now be described.

Disposed within the side frame 11 (Figures 1 and 4) is the slideable pin 64 having an eye 64a adapted to receive the extension pin 55. The upper extremity of the pin 64 is provided with a head 64b. The pin 64 is held in an uppermost position by means of the coil spring 64c engaging under said head 64b. Said pin 64 is controlled by the eccentric 65, which in turn is controlled by the small handle 66. With the handle 66 in the position shown in Figures 1 and 4, a short radius of the eccentric 65 will be in co-operative relationship with the pin 64 whereby the corresponding extension pin 55 will be allowed to assume a position in which the pins 53-53 do not have any effect in compressing the springs 52-52. The details of the eccentric 65 are not important in this description. Preferably, however, the eccentric or any

equivalent thereof should be overcentering whereby said eccentric or equivalent will remain in the position to which it is moved by the operator. When, however, the handle 66 5 is turned in a counter-clockwise direction, as the parts are viewed in Figures 1 and 4, through a ninety degree angle, a longer radius of the eccentric 65 will be in co-operative relationship with the pin 64, whereby the 10 pins 53 will be held against their corresponding rollers 51, holding the rollers 51 in the large portions of the recesses 49, thereby rendering ineffective any locking relationship between the member 46 and the fixed wedging 15 member 48.

The crank 43 for operating the drive shaft 27 will now be described. By reference to Figures 1 and 8 it will be noted that said crank comprises the hub 67 adapted to be 20 rigidly connected to the stub shaft 30 forming part of the drive shaft 27. Extending radially from the hub 67 are three arms 68, 69 and 70, the axes of said arms being disposed at one hundred and twenty degrees 25 angularity relative to one another. The arms 69 and 70 comprise radial handles. The arm 68 adjacent to its extremity is provided with the outstanding handle 71, extending in a direction parallel with the axis 30 of the drive shaft 27.

The legs 72 and the framework 73 for supporting the structure above described need not be described in detail inasmuch as such details form no part of the present invention. 35 Moreover, though in Figure 1 a carriage 74 has been illustrated in outline, no detailed description of the carriage is considered to be necessary inasmuch as carriages suitable for the purpose are commercially well 40 known.

The mode of operation of the above described embodiment of the invention is substantially as follows:

The description may be started with the 45 parts as they are located in Figure 1, with the spiral gear 25 at the rear of the machine in meshing relationship with the mating spiral gear 23. This position is assumed in a tightening operation or a rewinding operation upon the gelatin band 15. Assuming that the operator desires to move the 50 gelatin band forward, he will apply a turning force to the crank 43 to turn the shaft 27 in the direction of the arrow 75 in Figure 1. 55 At this time (see Figures 1, 2 and 5) the abutment member 61 is out of engagement with the extension pin 55 of the overrunning clutch 44 at the rear of the machine and said overrunning clutch is operative to prevent 60 clockwise movement of the member 46 as the parts are viewed in Figure 5. Turning movement of the shaft 27 will, by reason of the initial reaction of the spiral gears 25 and 23, result in axial movement of said shaft 27 65 in a forward direction, that is, to the right,

as the parts are viewed in Figure 1. This forward movement will continue until spiral gear 26 at the forward end of the machine partly meshes with spiral gear 24. After partial meshing of the spiral gears 26 and 24 70 at the forward end of the machine, the abutment member 60 will engage the extension pin 55 of the rear overrunning clutch 44, moving the pins 53, 53 in a counter-clockwise direction, as the parts are viewed in Figure 5, 75 holding the rollers 51 in the large portions of their corresponding tapering recesses 49. The rear clutch 44 will therefore be rendered inoperative to prevent rotation of the member 46 and the stub shaft 18 fast therewith. 80 Continued turning of the crank 43 to cause rotation of the shaft 27 in the direction of the arrow 75 (Figure 1) will cause continued forward movement of the shaft 27, that is, to the right, as the parts are viewed in Figure 1. This will result in the complete meshing of the spiral gear 26 with the spiral gear 24 and the demeshing of spiral gear 25 from spiral gear 23. Forward movement of the shaft 27 will be limited by engagement of the spiral gear 25 at the rear of the machine with the bifurcation 37 (Figure 1). Continued rotation of the crank 43 will result in the positive driving of the forward spindle 20 and the resultant dragging of the rear spindle 16. It may be explained at this point, reference being had to Figure 4, that clockwise rotation of the member 46, forming part of the forward overrunning clutch 45, is not interfered with, inasmuch as such clockwise rotation merely tends to move the rollers 51 toward the large portions of their corresponding tapering recesses 49. 90 95 100

When the operator has moved the gelatin band forward to the extent desired he may render said gelatin band taut by the simple expedient of reversing rotation of the handle 43, thereby turning the drive shaft 27 in the direction opposite to the arrow 75 (Figure 1). The first effect of such counter-rotation of the shaft 27 is, through the reaction of the spiral gears 26 and 24, to cause axial movement of the shaft 27 toward the rear, that is, toward the left, as the parts are viewed in Figure 1. This rearward movement of the shaft 27 will continue until intermeshing relationship is set up between the spiral gears 25 and 23 at the rear of the machine, which intermeshing relationship, as indicated hereinbefore, will be inaugurated 110 before intermeshing relationship between the spiral gears 26 and 24 at the forward end of the machine is interrupted. Rearward movement of the shaft 27 will continue until the spiral gear 26 is in abutting relationship 115 with the bifurcation 38 at which time the spiral gear 25 will be in full meshing relationship with the spiral gear 23. At this time a slight further counter-turning movement of the handle 43 to turn the shaft 27 in 120 125 130

the direction opposite to the arrow 75 will, through the spiral gears 25 and 23 and the stub shaft 18, result in a turning of the rear spindle 16 in a counter direction. In other words, the member 46 of the rear overrunning clutch 44 will move in a counter-clockwise direction, as the parts are viewed in Figure 5, the rollers 51 having no effect in stopping such counter-clockwise rotation of the member 46. However, at the forward end of the machine the rollers 51, forming part of the overrunning clutch 45, prevent the counter-clockwise rotation of the member 46 forming part of said overrunning clutch 45. At this time the overrunning clutch 44 at the rear of the machine and the overrunning clutch 45 at the forward end of the machine hold fast against the tension set up by the gelatin band 15, whereby said gelatin band 15 is held taut.

In some instances it is desirable to move the gelatin band 15 rearwardly either through a short section of its length or to rewind said gelatin band completely upon the rear spindle. In such cases the handle 66 (Figures 1 and 4) is turned in a counter-clockwise direction from that shown, whereby a long radius of the eccentric 65 is presented to the pin 64, moving the member 54 of the forward overrunning clutch 45 in a clockwise direction, as the parts are viewed in Figure 4. This movement will cause engagement between the pins 53 and the rollers 51, holding said rollers in the large portions of their corresponding recesses 49 and rendering the forward overrunning clutch inoperative. Under these conditions rotation of the crank 43 to turn the shaft 27 in the direction opposite to the arrow 75 will communicate a turning movement to the rear spindle and there will be no resistance to the rotation of the forward spindle inasmuch as the forward clutch 45 is inoperative, as immediately above described. When the operator has turned the gelatin band 15 as far as he desires, he will in normal operation move the handle 66 to the position indicated in Figures 1 and 4, allowing the pin 64, under the influence of the spring 64c to hold the pins 53 out of co-operative relationship with the rollers 51 in the clutch 45 at the forward end of the machine, whereby a counter-clockwise rotation of the member 46 and forward spindle 20 will be prevented. The overrunning clutch 44 at the rear of the machine and the overrunning clutch 45 at the forward end of the machine will therefore both resist the tension of the gelatin band 15, whereby said band will be maintained taut.

In this specification, when the distance between the spiral gears 25 and 26 is mentioned, it is intended to refer to the distance between the point in the pitch line of spiral gear 26, which coincides with the pitch line of the mating gear 24 when said gears 26 and 24 are

in complete meshing engagement and the point in the pitch line of the spiral gear 25 which coincides with the pitch line of the spiral gear 23 when said spiral gears 25 and 26 are in complete meshing engagement.

When the term spiral gear is used in this specification, it is intended to refer to the broad class of gearing such as worm gears and other evolutions of the spiral.

The term overrunning clutch is used to mean a device which, when operative, will produce operative engagement between a rotatable member and another member in one direction of rotation of said rotatable member, but which will prevent said rotatable member to rotate freely in the opposite direction of rotation of said rotatable member. Another term which might be used is "overrunning detent". Though a roller clutch is illustrated and described, it will be clear that clutching or detent means may be substituted having any other type of point or engaging means.

The present invention is designed to simplify the operations necessary to be performed by the operator of the machine. The crank 43 contributes toward this simplicity of operation. Ordinarily the operator will by standing in front of the machine and the bed 14 will be located at such a level that it will be convenient for the operator to manipulate the carriage 74. Under these conditions the crank 43 will be located slightly below the waist line of the operator. The operator will find it convenient to use the outstanding handle 71, forming part of the crank 43, but, if in the tightening operation, the handle 71 should be located at or near the lowermost part of its travel, the efficiency with which the operator may turn the crank 43 will be less than when said handle 71 is in any other part of its travel. Such position of the handle 71 is illustrated in Figure 8. Under these conditions the operator will find it very convenient to apply a downward force to the radially disposed arm 70, using the fleshy part of the palm of his hand for this purpose, if he prefers.

When the handle 71 is at or near that portion of its travel indicated by the line 76 in Figure 8, the operator will be exerting a lifting force upon said handle when he is performing a tightening operation. Under these conditions, particularly if the operator is a strong man, he is liable in his hurry to lift the machine together with its supporting framework from the floor, allowing it to drop with some force. Though the parts are so constructed that such handling will not be liable to damage the machine, nevertheless, such an operation may be annoying to persons in the vicinity. Under these conditions, the operator may exert a downward force upon the arm 69, again using the fleshy part of

the palm of his hand for this purpose, if he prefers.

From the foregoing description it will be noted that the invention provides a structure which may be made of sturdy parts, simple to manufacture and simple to operate. The number of different parts has been minimized, whereby the matter of stocking spare and repair parts is simplified. The operation of winding, tightening and rewinding is very simple, giving the unskilled operator very little chance to go wrong in the operation of the machine. By reason of the composite construction of the shaft 27, exact parallelism between the axes of the front and rear spindles is unnecessary, the fittings between the tubular member 28 and the shafts 29 and 30 being sufficiently loose in ordinary practice to provide the necessary accommodation of the parts, if the axes of said spindles at the front and rear of the machine should not be positioned with absolute accuracy. For this purpose it may be preferred by the manufacturer to leave a rather loose fitting between said tubular member 28 and the shafts 29 and 30.

It will be understood also that, if preferred, the spiral gears 25 and 26, instead of being spaced apart a distance less than the distance between the axes of the spindles 16 and 20, may be spaced apart a greater distance. For proper operation, however, the feature should be preserved that in the axial movement of the shaft 27 one of said spiral gears 25, 26 is enmeshed with its mating spiral gear before demeshing of the other of said spiral gears 25, 26 is accomplished. Moreover, the feature should be preserved that when one of the spiral gears 25, 26 is completely enmeshed with its mating spiral gears, the other of said spiral gears 25, 26 should be completely demeshed.

Though the preferred embodiment of the present invention has been described in detail, many modifications will occur to those skilled in the art. It is intended to cover all such modifications that fall within the scope of the appended claims.

What is claimed is:

1. In winding and tightening mechanism, in combination, an axially movable rotatable shaft, a pair of spiral gears secured to said shaft, a pair of second spiral gears adapted to mate alternately with said first mentioned spiral gears, and overrunning clutch means for controlling the rotation of said second spiral gears.

2. In winding and tightening mechanism, in combination, an axially movable rotatable shaft, a pair of spiral gears secured to said shaft, a pair of second spiral gears adapted to mate alternately with said first mentioned spiral gears, and overrunning clutch means for controlling the rotation of said second spiral gears, said first mentioned spiral gears

being spaced apart a distance less than the distance between the axes of said second spiral gears.

3. In winding and tightening mechanism, in combination, an axially movable rotatable shaft, a pair of spiral gears secured to said shaft, a pair of second spiral gears adapted to mate alternately with said first mentioned spiral gears, and overrunning clutch means for controlling the rotation of said second spiral gears, said first mentioned spiral gears being spaced apart a distance different than the distance between the axes of said second mentioned spiral gears.

4. In winding and tightening mechanism, in combination, a rotatable axially movable shaft, said shaft having mounted thereon a pair of spiral gears, a second pair of spiral gears adapted to engage selectively with said first mentioned spiral gears, said shaft having resilient means incorporated therewith to permit variation in the distance between said first mentioned spiral gears.

5. In winding and tightening mechanism, in combination, a shaft, spiral gears mounted upon said shaft, second spiral gears having fixed axes adapted to be enmeshed selectively with said first mentioned spiral gears, overrunning clutch members co-operating with said second spiral gears to limit the direction of rotation of each of said second spiral gears, and means controlled by said shaft for controlling the effectiveness of one of said clutches.

6. In winding and tightening mechanism, in combination, a shaft, spiral gears mounted upon said shaft, second spiral gears having fixed axes adapted to be enmeshed selectively with said first mentioned spiral gears, overrunning clutch members co-operating with said second spiral gears to limit the direction of rotation of each of said second spiral gears, and means controlled by said shaft for controlling the effectiveness of one of said clutches, said shaft being variable in length and having resilient means interposed therein to control the distance between said first mentioned spiral gears.

7. In winding and tightening mechanism, in combination, a pair of rotatable members adapted to control a pair of spools having a band connecting same, a longitudinally movable rotatable shaft, spiral gears carried by said shaft, second spiral gears adapted to be enmeshed selectively by said first mentioned spiral gears in response to axial movement of said shaft, said rotatable members being connected to said second spiral gears, clutches having co-operative relationship with said rotatable members, said clutches being adapted to resist pulling effect upon said rotatable members by said band, and means for selectively controlling the operativeness of said clutches.

8. In winding and tightening mechanism,

in combination, a pair of rotatable members adapted to control a pair of spools having a band connecting same, a longitudinally movable rotatable shaft, spiral gears carried by said shaft, second spiral gears adapted to be enmeshed selectively by said first mentioned spiral gears in response to axial movement of said shaft, said rotatable members being connected to said second spiral gears, clutches 10 having co-operative relationship with said rotatable members, said clutches being adapted to resist pulling effect upon said rotatable members by said band, and means responsive to the axial movement of said shaft for controlling the operativeness of one of said clutches.

9. In winding and tightening mechanism, in combination, a pair of rotatable members adapted to control a pair of spools having a band connecting same, a longitudinally movable rotatable shaft, spiral gears carried by said shaft, second spiral gears adapted to be enmeshed selectively by said first mentioned spiral gears in response to axial movement 25 of said shaft, said rotatable members being connected to said second spiral gears, clutches having co-operative relationship with said rotatable members, said clutches being adapted to resist pulling effect upon said rotatable members by said band, means responsive to axial movement of said shaft for controlling the operativeness of one of said clutches, and manually operable means for controlling the effectiveness of the other of said clutches.

35 10. In winding and tightening mechanism, in combination, an axially movable rotatable shaft, spiral gears mounted thereon, second spiral gears having their axes at right angles to said shaft, the spacing between said first mentioned spiral gears being less than the spacing between the axes of said second spiral gears, clutches controlling the rotation of said second spiral gears, said clutches being adapted under normal operation to permit 45 rotation of each of said second spiral gears in only one direction, and means responsive to axial movement of said shaft for controlling the operativeness of one of said clutches.

11. In winding and tightening mechanism, 50 in combination, an axially movable rotatable shaft, spiral gears mounted thereon, second spiral gears having their axes at right angles to said shaft, the spacing between the axes of said first mentioned spiral gears being less than the spacing between the axes of said second spiral gears, said clutches being adapted under normal operation to permit rotation of each of said second spiral gears in only one direction, means responsive to 55 axial movement of said shaft for controlling the operativeness of one of said clutches, and manual means for controlling the operativeness of the other of said clutches.

60 12. In winding and tightening mechanism, 65 in combination, an axially movable rotatable

shaft, spiral gears mounted thereon, second spiral gears adapted to co-operate with said first spiral gears, the spacing between said first mentioned spiral gears being different from the distance between the axes of said second spiral gears, said spacing being such that one of said first mentioned spiral gears is enmeshed with its mating second spiral gear before the other of said first mentioned spiral gears is demeshed from its mating second gear in the axial movement of said shaft, each of said first mentioned spiral gears being capable of complete disengagement from its mating second spiral gear in the axial movement of said shaft, said shaft being variable in length between said first mentioned spiral gears.

70 13. In winding and tightening mechanism, in combination, an axially movable rotatable shaft, spiral gears mounted thereon, second spiral gears adapted to co-operate with said first spiral gears, the spacing between the said first mentioned spiral gears being different from the distance between the axes of said second spiral gears, said spacing being such that one of said first mentioned spiral gears is enmeshed with its mating second spiral gear before the other of said first mentioned spiral gears is demeshed from its mating second gear in the axial movement of said shaft, each of said first mentioned spiral gears being capable of complete disengagement from its mating second spiral gear in the axial movement of said shaft, said shaft being variable in length between said first mentioned spiral gears, and resilient means disposed intermediate of the length of said shaft for controlling the distance between said first mentioned spiral gears.

75 14. In winding and tightening mechanism, in combination, an axially movable rotatable shaft, spiral gears mounted thereon, second spiral gears adapted to co-operate with said first spiral gears, the spacing between said first mentioned spiral gears being different from the distance between the axes of said second spiral gears, said spacing being such that one of said first mentioned spiral gears is enmeshed with its mating second spiral gear before the other of said first mentioned spiral gears is demeshed from its mating second gear, each of said first mentioned spiral gears being capable of complete disengagement from its mating second spiral gear in the axial movement of said shaft, said shaft being variable in length between said first mentioned spiral gears, and clutch means co-operatively associated with each of said second gears and adapted under normal operation to permit rotation of each of said second gears in one direction only.

80 15. In winding and tightening mechanism, in combination, an axially movable rotatable shaft, spiral gears mounted thereon, second spiral gears adapted to co-operate with said

first mentioned spiral gears, the spacing between the said first mentioned spiral gears being different from the distance between the axes of said second spiral gears, said spacing being such that one of said first mentioned spiral gears is enmeshed with its mating second spiral gear before the other of said first mentioned spiral gears is demeshed from its mating second gear in the axial movement of said shaft, each of said first mentioned spiral gears being capable of complete disengagement from its mating second spiral gear in the axial movement of said shaft, said shaft being variable in length between said first mentioned spiral gears, resilient means disposed intermediate of the length of said shaft for controlling the distance between said first mentioned spiral gears, and clutch means co-operatively associated with each of said second gears and adapted under normal operation to permit rotation of each of said second gears in one direction only.

16. In winding and tightening mechanism, in combination, an axially movable rotatable shaft, spiral gears mounted thereon, second spiral gears adapted to co-operate with said first mentioned spiral gears, the spacing between said first mentioned spiral gears being different from the distance between the axes of said second spiral gears, said spacing being such that one of said first mentioned spiral gears is enmeshed with its mating second spiral gear before the other of said first mentioned spiral gears is demeshed from its mating second gear, each of said first mentioned spiral gears being capable of complete disengagement from its mating second spiral gear in the axial movement of said shaft, said shaft being variable in length between said first mentioned spiral gears, clutch means co-operatively associated with each of said second gears and adapted under normal operation to permit rotation of each of said second gears in one direction only, and means responsive to axial movement of said shaft for controlling the operativeness of one of said clutches.

17. In winding and tightening mechanism, in combination, an axially movable rotatable shaft, spiral gears mounted thereon, second spiral gears adapted to co-operate with said first mentioned spiral gears, the spacing between said first mentioned spiral gears being different from the distance between the axes of said second spiral gears, said spacing being such that one of said first mentioned spiral gears is enmeshed with its mating second spiral gear before the other of said first mentioned spiral gears is demeshed from its mating second gear, each of said first mentioned spiral gears being capable of complete disengagement from its mating second spiral gear in the axial movement of said shaft, said shaft being variable in length between said first mentioned spiral gears, re-

silient means disposed in said shaft for controlling the distance between said first mentioned spiral gears, clutch means co-operatively associated with each of said second gears and adapted under normal operation to permit rotation of each of said second gears in one direction only, and means responsive to axial movement of said shaft for controlling the operativeness of one of said clutches.

18. In winding and tightening mechanism, in combination, an axially movable rotatable shaft, spiral gears mounted thereon, second spiral gears adapted to co-operate with said first mentioned spiral gears, the spacing between said first mentioned spiral gears being different from the distance between the axes of said second spiral gears, said spacing being such that one of said first mentioned spiral gears is enmeshed with its mating second spiral gear before the other of said first mentioned spiral gears is demeshed from its mating second gear, each of said first mentioned spiral gears being capable of complete disengagement from its mating second spiral gear in the axial movement of said shaft, said shaft being variable in length between said first mentioned spiral gears, clutch means co-operatively associated with each of said second gears and adapted under normal operation to permit rotation of each of said second gears in one direction only, means responsive to axial movement of said shaft for controlling the operativeness of one of said clutches, and manually operable means for controlling the operativeness of the other of said clutches.

19. In winding and tightening mechanism, in combination, an axially movable rotatable shaft, spiral gears mounted thereon, second spiral gears adapted to co-operate with said first mentioned spiral gears, the spacing between said first mentioned spiral gears being different from the distance between the axes of said second spiral gears, said spacing being such that one of said first mentioned spiral gears is enmeshed with its mating second spiral gear before the other of said first mentioned spiral gears is demeshed from its mating second gear, each of said first mentioned spiral gears being capable of complete disengagement from its mating second spiral gear in the axial movement of said shaft, said shaft being variable in length between said first mentioned spiral gears, resilient means disposed in said shaft for controlling the distance between said first mentioned spiral gears, clutch means co-operatively associated with each of said second gears and adapted under normal operation to permit rotation of each of said second gears in one direction only, means responsive to axial movement of said shaft for controlling the operativeness of one of said clutches, and manually oper-

- able means for controlling the operativeness of the other of said clutches.
20. In winding and tightening mechanism, in combination, a pair of spindles, a band connecting said spindles, clutches co-operatively associated with each of said spindles and adapted under normal circumstances to prevent the turning of said spindles under the pull of said band, an axially movable shaft for selectively communicating turning movements to said spindles, means responsive to axial movement of said shaft for controlling the operativeness of one of said clutches.
- 15 21. In winding and tightening mechanism, in combination, a pair of spindles, a band connecting said spindles, clutches co-operatively associated with each of said spindles and adapted under normal circumstances to prevent the turning of said spindles under the pull of said band, an axially movable shaft for selectively communicating turning movements of said spindles, means responsive to axial movement of said shaft for controlling the operativeness of one of said clutches.
- 20 22. In winding and tightening mechanism, in combination, an axially movable rotatable shaft, said shaft having spiral gears mounted thereon, second spiral gears adapted to be enmeshed selectively with said first mentioned spiral gears, said shaft being composite in its nature having a central portion and two end portions loosely connected to said central portion, said first mentioned spiral gears being located upon said end portions.
- 25 23. In winding and tightening mechanism, in combination, an axially movable rotatable shaft, said shaft having spiral gears mounted thereon, second spiral gears adapted to be enmeshed selectively with said first mentioned spiral gears, said shaft being composite in its nature having a central portion and two end portions loosely connected to said central portion, said first mentioned spiral gears being located upon said end portions, said shaft being variable in length and being provided with resilient means for controlling the distance between said first mentioned spiral gears.
- 30 24. In a hectograph machine, in combination, a relatively stationary portion, a carriage movable along said relatively stationary portion, gelatin band winding and tightening mechanism co-operatively associated with said relatively stationary portion, and an operating shaft for said winding and tightening mechanism, said shaft being disposed in parallelism with the line of movement of said carriage, said rotary shaft being provided with a crank for manual operation thereof, said crank having two radially disposed arms extending from the axis of said shaft at 120 degrees from one another, and a handle spaced from the axis of said shaft, said handle having its axis parallel with said shaft and disposed in 120 degrees angular relationship with said arms.
- 35 25. In a hectograph machine, in combination, a bed, a carriage movable along said bed, a shaft parallel with the line of movement of said carriage, winding and tightening mechanism for a hectograph band adapted to be controlled in the rotation of said shaft, and a crank for said shaft, said crank having two arms extending radially at 120 degrees to one another relative to the axis of said shaft, said crank also having an outstanding handle spaced from the axis of said crank, said handle having its axis parallel with the axis of said crank and being disposed in a plane in 120 degrees relationship with said arms.
